UNITED STATES PATENT OFFICE.

SMITH H. FINCH, OF NEW YORK, N. Y., AND HENRY MOORE, OF ORANGE,
NEW JERSEY.

IMPROVEMENT IN SWITCH AND SIGNAL LOCKING DEVICES.

Specification forming part of Letters Patent No. 179,290, dated June 27, 1876; application filed
May 1, 1876.

To all whom it may concern:

Be it known that we, SMITH H. FINCH, of the city, county, and State of New York, and HENRY MOORE, of Orange, in the county of Essex and in the State of New Jersey, have invented a new and Improved Switch and Signal Lever Locking Device, of which the following is a specification:

Figure 1 is a front view of a pair of levers to which our improvement has been applied, the stand being shown in section. Fig. 2 is a side view of the same, the stand being shown in section through the line $x x$, Fig. 1. Fig. 3 is a detail view of one of the sliding bars.

The object of this invention is to furnish an improved attachment for switch and signal levers, which shall be so constructed that the movement of the detent to release a lever will lock the other levers, or any previously arranged number of them, before the said lever has begun to move, and so that the said levers cannot be moved until the first one has been brought back to its place and secured by its detent.

The invention consists in the combination of the pins and the hooks of the sliding bars, with the slotted lugs and the holes of the detents of the levers, as hereinafter fully described.

A represents the stand to which the levers are pivoted, and B represents the slotted guides through which they move. C are the levers, which are connected with the switches or signals in the usual way. D are the detents, which slide in guides along the rear

sides of the levers C, and engage with notches in the guides B to keep the said levers in place when adjusted.

The detents D are extended along the rear side of the levers C, and have lugs d^1 formed upon the sides of their lower parts, in which are formed inclined slots, to receive pins e^1 attached to the bars E. The bars E slide in guides in the stands A, and to them are attached hooks e^2 , one for each lever, to be locked by the movement of the detent of one of said levers, and which hook into holes d^2 in the detents of said levers.

By this construction, as one of the detents D is raised to release its lever C, the inclined slot of the lug d^1 acts upon the pin e^1 of the sliding bar E, and forces the hooks e^2 of said bar into holes d^2 in the detents D of the other levers C, so that the said levers will be locked before the lever being operated begins to move, and will be held locked until said lever has been brought back to its place, and the detent has dropped into place.

Having thus described our invention, what we claim as new, and desire to secure by Letters Patent, is—

The combination of the pins e^1 and the hooks e^2 of the sliding bars E, with the slotted lugs d^1 and the holes d^2 of the detents D, substantially as herein shown and described.

SMITH H. FINCH.
HENRY MOORE.
